CLAIM

I claim the ornamental design for the reflective oven for S'mores, as shown and described.

DESCRIPTIONFIG. 1 is a top view of the reflective oven for S'mores.
 FIG. 2 is a bottom view of the claimed design.

FIG. 3 is a left side view of the claimed design.

FIG. 4 is a front view of the claimed design.

FIG. 5 is a rear view of the claimed design; and,
 FIG. 6 is a perspective view of the claimed design folded for
 in use.The broken lines of FIG. 1 are environmental matter forming
 no part of the claimed design.**1 Claim, 4 Drawing Sheets**FIG. 1

FIG. 2

FIG. 3

FIG. 4

FIG. 5

FIG. 6
